UNITED STATES PATENT OFFICE

EMMA S. ROOT, OF LOS ANGELES, CALIFORNIA

QUILTING FRAME

Application filed March 17, 1927. Serial No. 176,207.

This invention relates to improvements in quilting frames and has as its general object to provide a frame which will present advantages over quilting frames now in use.

One of the objects of the present invention is to provide, in a quilting frame embodying rolls from which the lining and cover plies of the quilt is to be unwound and a roll upon which the finished quilt is to be wound, novel means for supporting the roll from which the cover ply is to be unwound, the means being so constructed that this roll may be readily and quickly adjusted to an elevated position so as to permit of the disposal of the filling upon the lining ply which extends between the roll from which the lining ply is to be unwound and the roll upon which the finished quilt is to be wound, and which supporting means will be so constructed and capable of operation in such a manner as to permit of more ready and rapid disposal of the filling and its arrangement and, when the means is operated to lower the roll supported thereby to its lowered position, will constitute means for tensioning the cover ply of the quilt being produced.

Another object of the invention is to provide means for supporting the roll from which the cover ply of the quilt is to be unwound, which means will be so constructed that when it is adjusted to bring the said roll to its lowered position, the cover and lining plies of the quilt will be maintained in parallelism while the quilting operation is being performed.

Another object of the invention is to provide novel means for preventing any backward rotation of any of the rolls of the quilting frame so that the plies will be at all times properly tensioned.

Another object of the invention is to provide novel means whereby the quilting frame as a whole may be bodily adjusted with respect to its suspension means so as to compensate for increase in weight at one side of the frame occasioned by the progressive formation of the quilt and the winding of the quilt upon the roll upon which it is wound as the quilting operation progresses.

50 In the accompanying drawings:

Fig. 1 is a view in side elevation illustrating the quilting frame embodying the invention;

Fig. 2 is a top plan view of the said frame, a portion of the completed quilt being broken away as also a portion of the covering for the roll upon which the completed quilt is to be wound;

Fig. 3 is an end elevation of the frame illustrating the roll and supporting means therefor, which roll is the one from which the cover ply of the quilt is to be unwound, in elevated position in dotted lines;

Fig. 4 is a vertical front to rear sectional view through the quilting frame illustrating the storage roll for the cover ply in elevated position and the manner in which the filling is to be arranged between the plies;

Fig. 5 is an end elevation, partly in section, of the frame and the suspension means therefor and illustrating the manner in which the frame is suspended for adjustment to compensate for over-balancing;

Fig. 6 is a bottom plan view of one end of the frame;

Fig. 7 is a view similar to Figure 4 illustrating the storage roll for the top ply of the quilt in lowered position.

The quilting frame embodying the invention is indicated in general by the numeral 1 and the frame is supported by an overhead suspension means which will presently be specifically described.

The quilting frame comprises a pair of side members 2 suspended by the means referred to above, in parallel spaced relation with respect to each other, and these side members rotatably support the three rolls of the frame which rolls are indicated one by the numeral 3, another by the numeral 4, and the third by the numeral 5. The rolls 3 and 5 are provided at their ends with trunnions 6' which are journaled in the side members 2 so that the rolls are independently rotatable between the said side members. The roll 4 is rotatably supported between the side members 2 by a means which will presently be described. As will presently be made clear, the roll 3 constitutes a storage roll for the lining material or ply of the quilt; the roll 4 constitutes a 100

storage roll for the cover ply of the quilt; and, the roll 5 constitutes a take-up roll for the completed quilt. The means for supporting the roll 4 comprises a pair of arms 6 which are pivotally mounted as at 7 at one end in recesses 8 formed in the inner sides of the respective side members 2 of the quilting frame, the recesses opening through the upper sides of the side members and through the inner sides thereof and being of dimensions to preferably substantially exactly receive the respective arms 6. The trunnions at the outer ends of the roll 4, which trunnions are indicated by the numeral 9, are journaled in openings 10 provided in the outer ends of the arms 6. At this point it will be evident that when the arms are in the lowered position shown in full lines in Fig. 7 of the drawings and likewise in Fig. 2, the roll 4 will be supported in a lowered position and it will likewise be observed by reference to the said Fig. 7 that the pivots for the arms 6 are located slightly above the longitudinal axes of the rolls 3 and 5. It will likewise be evident by reference to Fig. 7 that the axis of the roll 4 is in the same horizontal plane as that in which the pivots 7 are located and consequently the axis of the roll 4 is slightly elevated with respect to the axes of the rolls 3 and 5. As will be evident by reference to the said Fig. 7, this relative upward displacement of the roll 4 with respect to the rolls 3 and 5 serves to position the cover ply of the quilt in a plane parallel to but spaced above the lining ply thereof so that during the quilting operation in which the quilting stitches are run through the two plies and through the filling at those portions of the plies which extend between the rolls 4 and 5, the plies occupy parallel planes and obviously this is of advantage as, if the filling has been properly laid, the quilt will be of uniform thickness throughout its entire area when it is completed. It is not required that any means be provided for supporting the arms 6 in the elevated position shown in full lines in Fig. 4 of the drawings for in such position the arms are directly vertical and the upper edge of each arm, at the pivoted end thereof, will abut against the corresponding end wall of the recess 8 as shown in the said figure. At this point it will be understood, and particularly by reference to Figure 4, that when the arms 6 are swung to the elevated position shown in said figure the pivots 7 for the said arms will be located forwardly of the plane occupied by the forward sides of the cover ply storage roll 4 and quilt take-up roll 5 and, inasmuch as the cover ply C is somewhat tensioned, and extends between these rolls, there will be no tendency for the arms 6 to swing downwardly.

Each of the rolls 3, 4 and 5 is provided with a wrapping or cover 11 of any suitable fabric which is applied thereto and extends substantially throughout the entire length of the roll,

although in the drawings, for the sake of clearness in illustrating the roll, this fabric has been omitted except in Figures 2, 4 and 7. The purpose of the fabric covering upon each roll is to provide a means whereby, in the instance of the rolls 3 and 4, the lining and cover plies of material which go to make up the quilt may be more readily wound upon the respective rolls by temporarily and separately uniting the margin of the respective ply to the said cover or, if it is not desired to actually unite the plies to the covers of the respective rolls, the covers constitute a friction surface which will insure of winding of the plies onto the rolls prior to arrangement of the rolls in the quilting frame of the invention. In a like manner the covering of fabric upon the roll 5 constitutes a means whereby the first finished edge of the quilt may be temporarily attached to the roll so that the quilt may be evenly and with certainty wound about the roll when the roll is rotated during the quilting operation and from time to time as the operation progresses. Preferably the rolls 3, 4 and 5 are of wood and approximately rectangular in cross-section as shown in the sectional views of the drawings, the edges being however preferably beveled. The advantage gained by forming the rolls of this contour is that the coverings 11' for the rolls will adhere frictionally thereto and there will be little likelihood of slipping of the coverings or the plies or finished quilt wound upon the rolls.

It is of course necessary that means be provided for holding the several rolls against rotation, so that the cover and lining plies of the quilt and the partially completed quilt itself will not sag due to unwinding of the same from the respective rolls and as the means provided for this purpose in connection with each roll is the same, a description of the means as applied to one roll will suffice for all. The said means comprises a wheel 11 which is fixed upon one of the trunnions 9 of each of the rolls and this wheel functions in the manner of a ratchet except that it differs from the ordinary ratchet in that its teeth resembles gear teeth. A pawl indicated by the numeral 12 is mounted upon that one of the side members 2 of the frame next to which the ratchet wheels 11 are located, these ratchet wheels being arranged between the said side member of the frame and the adjacent ends of the respective rolls, and one of the pawls is of course mounted adjacent each of the said ratchet wheels. Each pawl may be conveniently formed from resilient wire material or light rod material and comprises a portion 13 which is mounted for rocking movement in an opening provided in the side member 2 parallel to the trunnions 9 of the respective roll, and this portion 13 is provided at one end with a right angularly extending arm 14 having an in-

turned end 15 which serves the purpose of a pawl and is designed to engage between the teeth of the respective ratchet wheel 11 in the manner most clearly shown in Figures 2 and 3 of the drawings, when the pawl is 5 rotatably adjusted to one position of adjustment. At its other end the portion 13 is provided with a finger piece 16 which extends at right angles from the said end of the portion 13 and has its end overturned in an inward direction as at 17 to rest frictionally against the outer face of the said side member 2 of the frame. The finger piece 16 is preferably of greater length than the member 14 of each pawl and while the end 15 of the arm 14 of each pawl is preferably frictionally in engagement with the inner side of the said side member 2 of the frame and the overturned end 17 of the finger piece 16 of the same pawl is frictionally in engagement with the outer face of the said frame side member so as to insure of the pawl being held in either position of adjustment or in other words with the end 15 of its arm 14 either in or out of engagement with the respective ratchet wheel 11, it will be understood that the pawl might be loosely mounted. The frictional engagement is however of advantage inasmuch as when the 30 pawls are so arranged and constructed, and are adjusted to position out of engagement with the respective ratchet wheels, they will be supported in such position. It will also be observed that by overturning the outer 35 end 17 of the finger piece 16 of each pawl, the said finger piece is sufficiently spaced from the outer face of the side member 2 of the frame to permit of its being readily grasped for the purpose of adjusting the 40 pawl.

Assuming that the quilting operation has progressed to the stage illustrated in Fig. 7 of the drawings in which figure the lining ply of the quilt is indicated by the reference letter L, the cover ply by the reference letter C, the filling by the reference letter F, and the quilting stitches by the letter S, the pawl for the ratchet wheel upon the roll 4 is swung to position clearing the said wheel and the 45 roll 4 is swung bodily upwardly to the elevated position shown in Fig. 4 of the drawings. At the same time the pawls for the ratchet wheels of the rolls 3 and 5 are moved to disengaged position and so much of the 50 quilt as has been completed and which comprises the quilted portion extending between the rolls 4 and 5 in Fig. 7, is wound upon the roll 5 by rotating the said roll until the last row of quilting stitches S is relatively close to the completed portion of the quilt which is 55 wound upon the said roll 5 as shown in Fig. 4 at which time the ratchet for the roll 3 is adjusted to engaging position and the roll 5 is rotated so as to tension the lining ply 60 L by winding up a further relatively short

portion of the partly completed quilt upon the said roll 5. The filling F is then arranged in suitable quantity upon the lining ply L which at such time is stretched taut as shown in Fig. 4, and for a portion of the length 70 of the said lining ply substantially equivalent to that illustrated in the said figure or in other words for such portion of the length as is determined by the last line of quilting stitches S and a point substantially coincident with the end of the recess 8. When the filling has been evenly distributed, the arms 6 are swung downwardly so as to 75 restore the roll 4 to its original lowered position and at such time the roll is manually rotated so as to tension the cover ply C and the pawl for the ratchet wheel upon this roll is then adjusted to engage the said ratchet wheel so that the roll is held against rotation. At this time the plies L and C will be 80 under tension and the filling F will be more or less compressed between the plies. The quilting operation is then performed until the quilting stitches have been run substantially to the extent shown in Fig. 7 or in other 85 words until the last formed row of stitches is very close to the roll 4 whereupon the previously described operation is repeated.

From the foregoing description of the frame embodying the invention it will be 90 seen that the frame is most efficient in its operation and that quilting may be more readily, accurately, and neatly performed than has heretofore been possible with previously employed quilting frames.

An overhead suspension means is provided for the quilting frame embodying the invention and in the drawings the numeral 18 indicates a trolley wire or rod upon which there is supported, by rollers 19, a carriage 20 having depending plates 21 secured to its opposite sides and extending downwardly therefrom, each of these plates being provided with a vertical longitudinally extending series of openings 22. A beam 23 is provided with similar plates 24 bolted or otherwise secured thereto but the beam 23 is of a thickness greater than the transverse dimensions of the carriage 20 so that the upper portions of the plates 24 overlap the lower portions of the 105 plate 21. Bolts 25 are secured through openings in the plates 24 and selectively through the openings 22 in plates 21 and in this manner vertical adjustment is provided for. The numeral 26 indicates a bar which is suspended by rods 27, at its ends, from the ends of the beam 23, and the numeral 28 indicates wire loops of inverted V-form which at their upper or minor ends are suspended from eyelets 29 upon the under side of the bar 26. The 110 loops 28 are continuous and are of heavy wire but at the same time a quality of wire possessing some degree of flexibility and the loops extend downwardly and through openings 30 formed in the side members 2 of the frame 115

near the ends thereof, the portion of the wire constituting the bottom of the loop and indicated by the numeral 31, engaging in a longitudinal groove 32 formed in the under side of the said frame member 2 as best shown in Fig. 5 of the drawings. At this point it will be understood that after a considerable length of completed quilt has been wound upon the roll 5 the tendency will be to overbalance the frame but by bodily adjusting the frame by tilting the same, the frame may be positioned to overcome the overbalancing.

It is to be understood, of course, that various changes may be made, within the scope of what is claimed, without departing from the spirit of the invention.

Having thus described the invention, what I claim is:

1. A quilting frame comprising side members, a lining ply storage roll mounted between the members at the front thereof, a quilt take-up roll also mounted between the said members at the rear thereof, arms pivotally mounted upon the said side members between said rolls, means upon the side members for supporting the said arms in a lowered substantially horizontal position beside the side members, the arms being swingingly adjustable to assume upright positions, means upon the said side members engageable by the arms to limit their movement to such position whereby they may be supported in upright position, and a cover ply storage roll supported between the said arms, the last mentioned means coacting with the arms at a point forwardly of the plane occupied by the forward sides of the cover ply storage and quilt take-up rolls.

2. A quilting frame comprising side members, a lining ply storage roll mounted between the members at the front thereof, a quilt take-up roll also mounted between the said members at the rear thereof, arms pivotally mounted upon the said side members between said rolls, means upon the side members for supporting the said arms in a lowered substantially horizontal position beside the side members, the arms being swingingly adjustable to assume upright positions, means upon the said side members engageable by the arms to limit their movement to such position whereby they may be supported in upright position, and a cover ply storage roll supported between the said arms the last mentioned means coacting with the arms at a point forwardly of the plane occupied by the forward sides of the cover ply storage and quilt take-up rolls the pivots for the said arms being located in a plane above the planes of the axes of the first mentioned rolls and the cover ply storage roll being so mounted upon the arms that its axis will occupy a common horizontal plane with the axes of the pivots for the arms, the said axes for the pivots for the arms being located in a plane

spaced above the plane occupied by the axes of the first mentioned roll a distance approximating the thickness of the quilt.

3. In a quilting frame, the combination with the side members of the frame, of a roll having trunnions journaled in said side members, a ratchet wheel upon one of the trunnions located beside the adjacent side member of the frame, and a resilient pawl having a portion rotatably mounted in the said side member of the frame and having a resilient arm extending from one end thereof beside said side member of the frame and provided with a laterally directed end for coacting with the teeth of the ratchet wheel and likewise engaging the adjacent side of the said side member of the frame, an arm extending from the other end of the rotatably mounted portion of the pawl beside the other side of the said side member of the frame and having a finger piece engaging the same and held frictionally in contact therewith through the resiliency of the said pawl member.

In testimony whereof I affix my signature.

Mrs. EMMA S. ROOT.
